UNITED STATES PATENT OFFICE.

JOHN H. CROSS, OF MINNEAPOLIS, MINNESOTA, ASSIGNOR TO THE WATERMAN-WATERBURY COMPANY, OF MINNEAPOLIS, MINNESOTA, A CORPORATION OF MINNESOTA.

CRESCENT RADIATOR.

Application filed December 30, 1926. Serial No. 157,993.

This invention relates to improvements in furnaces and is particularly directed to improvements in that portion of the hot air furnace known as the crescent radiator. 5 This radiator is attached at the rear of the main radiator, and both are surrounded by the outer radiating casing.

An object of the present invention is to produce a thorough circulation of air in the 10 radiator, and at the same time cause the heated air to be spread or directed to engage and heat the maximum area of the radiating surface. Another object of the invention is to properly spread the heat in the manner 15 above mentioned, but to positively prevent choking of the circulation. Another object of the invention is to cause the entire column of the heated air to be carried laterally thence to the bottom of the radiator then 20 across the bottom in direction of greatest dimension and finally upwardly and out of the stack, this giving the column a zig-zag substantially triangular path, having its apex at level of the smoke flues.

25 Features of the invention include all the details of construction, as well as the general arrangement of the baffle elements to direct the entire column of heated air downwardly thence across and then upwardly.

30 In the accompanying drawings forming a part of this application

Figure 1 is a vertical section showing my invention applied in a crescent radiator, in conjunction with a hot air furnace;

35 Figure 2 is a horizontal section, the section being taken through the outer casing of the heater or furnace;

Figure 3 is a horizontal section taken substantially on line 3-3 of Figure 1 and

40 Figure 4 is a vertical section through the radiator taken substantially on the line 4-4 of Figure 3.

Numeral 1 designates the furnace casing and 2 the crescent radiator. The crescent 45 radiator is supported at the bottom by a bracket 4 and at the top by the connected flanged flue extensions 5 and 6. A thimble 7 extends through the connected flanged flue extensions as shown. This construction 50 may be viewed as constituting the intake flue for the crescent radiator. The smoke flue is indicated at 9. The thimble 7 and flue 9 are horizontally alined. It is to be understood that elements 7 and 9 constitute

aligned smoke outlet flues. Adjacent the 55 lower end, the crescent radiator is provided with a clean-out flue 10.

Arranged within the radiator, and attached to and depending from the top, is a vertical partition 15 in this instance having 60 oppositely extending curved terminal portions which are respectively connected as at 16-17 with the outer and inner walls 19-20 of the radiator. The partition 15 has centrally thereof a damper 25 suitably mounted 65 upon a rotatable rod 26, and arranged to close the opening 28. This rod extends upwardly through the top of the crescent radiator and has a suitable arm 30 having an operating link or rod 31 extending to the 70 front of the heater. The opening 28 is horizontally alined with the elements 7 and 9. The partition 15 extends downwardly well towards the bottom of the radiator, but is spaced thereabove substantially as shown 75 in Figures 1 and 4.

In order to cause the products of combustion to be first directed downwardly toward the bottom surface of the radiator, and then caused to travel horizontally and then 80 rise, I provide a pair of baffles 35-36 which are slantingly arranged at opposite sides of the flue partition below the level of the flues, the baffles being slanted in opposite directions, and being extended outwardly beyond 85 and downwardly below the bottom of the partition. The upper end of the baffle 35 is disposed substantially as shown while the lower end projects laterally of the flue partition and downwardly as best shown in Figures 3 and 4. The other baffle 36 extends in the opposite direction and the baffles are substantially symmetrically related as viewed in edge view, for instance as in Figure 4. The lower end 40 of each of the 90 baffles is spaced from each end 41 of the radiator, in such a manner that the circulating spaces designated 42 are of approximately the same or of slightly larger area 95 than that of the elements 7 and 9. This is to secure free circulation of the products of combustion. After passing downwardly at the inner side of the radiator the products of combustion are forced entirely across the same in direction of its greatest horizontal dimension, and then rise and pass in an opposite direction upwardly to the flue 9. The 100 baffles are preferably cast integral with the 105

partition 15, so that the plate with its baffles and a unit may be placed in position, or withdrawn therefrom. However, the arrangement of the baffles is the important 5 feature.

The products of combustion are not divided, as they enter at the vertical middle of the radiator from the combustion chamber, but are wholly directed downwardly, 10 then completely across the bottom portion of the radiator in the direction of greatest horizontal or circumferential dimension, and are then directed upwardly and inwardly, to the vertical middle of the radiator, and to 15 the smoke stack.

It will be further noted that the disposition of the lower ends of the baffles in reference to the adjacent front rear and end walls of the radiator is such that a free circulation 20 of products of combustion around the ends of the baffles is obtained.

I claim as my invention:

1. A crescent radiator including smoke inlet and outlet flues, a partition depending 25 between the flues and having its lower end adjacent the bottom of the casing, and a baffle arranged laterally one at each side of the partition, below the level of the flues and slanting in opposite directions and engaging 30 the walls of the radiator, and having their lower ends arranged with reference to the radiator walls to form circulation openings adjacent the bottom of the radiator, and at 35 opposite ends of the casing in direction of the greatest horizontal dimension.

2. A crescent radiator including smoke inlet and outlet flues, a partition depending from the casing and separating the flues, and having its lower end adjacent the bottom of 40 the casing, and a baffle arranged laterally at each side of said partition to cause the products of combustion to pass laterally and downwardly from one of the outlet flues, thence laterally and horizontally in direction of longest dimension of the radiator 45 adjacent the bottom, then upwardly and laterally in the opposite direction to the other outlet flue.

3. A crescent radiator including alined 50 smoke inlet and outlet flues, adjacent its upper portion a vertical partition depending from the top of the casing and separating the flues, and having its lower end adjacent the bottom of the casing, and a baffle ar- 55 ranged laterally at each side of said partition and slanting in opposite directions, and

having their lower ends extended beyond the partition in opposite directions to a point adjacent the bottom of the radiator, the ends being arranged to form circulation openings. 60

4. A crescent radiator including radially arranged, alined, smoke inlet and outlet flues, a vertical partition depending from the top of the casing passing between the flues and spaced from the open end thereof, 65 and having its lower end adjacent but spaced upwardly from the bottom of the casing, a damper in said partition in opposition to said flues, and a baffle arranged laterally at each side of said partition below the level of 70 the flues and slanting in opposite directions, and having their lower ends extended beyond the partition in opposite directions to a point adjacent the bottom of the radiator, the ends being arranged with reference to 75 the walls of the radiator to form circulation openings, and the front and rear edges of said baffles being substantially sealingly engaged with the corresponding faces of the 80 radiator casing, and depending partition.

5. A partition for a crescent radiator having a slantingly arranged plate extending from each opposite side, said plates slanting in opposite directions, and said plate marginally formed and said plates having outer 85 edges arranged to engage the walls of the radiator.

6. A crescent radiator including smoke inlet and outlet flues, a partition depending between the flues, and a baffle laterally ar- 90 ranged one at each side of the partition, said baffles slanting in opposite directions and engaging the walls of the radiator, and having their lower ends arranged adjacent the 95 bottom of the radiator to form a circulation passage at opposite ends of the casing, in direction of the greatest horizontal dimension.

7. A crescent radiator including smoke inlet and outlet flues, a vertical partition separating the flues, and baffles arranged lat- 100 erally one at each side of said partition to cause the products of combustion to pass laterally and downwardly from one of the outlet flues, thence laterally and horizontally in direction of the longest dimension of the ra- 105 diator and adjacent the bottom, and then upwardly and laterally in the opposite direction to the other outlet flue.

In witness whereof, I have hereunto set my hand this 22nd day of December 1926.

JOHN H. CROSS.
